UNITED STATES PATENT OFFICE.

BENJAMIN GROSS, OF NEW YORK, N. Y., ASSIGNOR TO BENJAMIN & EDWARD J. GROSS CO. INC., OF NEW YORK, N. Y., A CORPORATION OF NEW YORK.

DESIGN FOR A FINGER RING OR ARTICLE OF SIMILAR NATURE.

Application filed May 28, 1926. Serial No. 17,877. Term of patent 3½ years.

To all whom it may concern:

Be it known that I, BENJAMIN GROSS, a citizen of the United States, residing at New York city, in the county of New York and State of New York, have invented a new, original, and ornamental Design for a Finger Ring or Article of Similar Nature, of which the following is a specification, reference being had to the accompanying drawing, forming a part thereof.

Fig. 2 is an edge view thereof.

I claim:

The ornamental design for a finger ring, or article of similar nature, as shown.

In testimony whereof I affix my signature.

BENJAMIN GROSS.
